STRUCTURAL FRAME

Elmer W. Coleman, Jamestown, N. Y., assignor to
Dahlstrom Metallic Door Company, Jamestown, N. Y., a corporation of New York

Application August 8, 1931, Serial No. 555,927

8 Claims. (Cl. 189—34)

This invention relates to an improvement in structural frame work and more particularly to an arrangement for retaining shelving for libraries, reference files, and also frames for filing 5 drawers, bins, etc., in buildings where considerable space is devoted to a systematic method of storage.

The preferred embodiment of this invention discloses a structure comprising a plurality of spaced 10 upright supporting members, substantially star-shaped in cross section, which are secured to the floor. Rectangular deck plates are arranged and supported at convenient vertical intervals to any desired height. The structure obtains its lateral 15 support by engaging the walls of the building or anchoring directly to the structure which supports the walls. Longitudinal support of the structure is had through cross tie rods which are provided with turnbuckles for tightening to the 20 desired tension. The upper surface of the deck plates are adapted to receive any suitable composition or other sheet flooring. The edges of the deck plates terminate in flanges which serve to resist the tendency to deflect or buckle.

25 Heretofore, in structures of this nature, the only available floor space during process of erection was the ground floor. In applicant's structure, however, the deck plates which are placed in position as erection progresses, provide a safe 30 support for the workman as well as for the material to be used in assembling the next tier.

This invention reveals as its principal object 35 a structure for supporting library shelving, etc., having a substantially integral deck formed by a plurality of deck plates at each floor level.

Another object of the invention lies in the provision of a supporting structure for library stacking, filing shelves, etc., comprising upright 40 members of substantially star-shaped cross section to which deck plates are attached.

A further object of the invention is to provide, 45 in a structure for supporting library stacking, means for rigidifying each individual tier against longitudinal displacement.

A still further object of the invention lies in the provision of a library stacking structure having a relatively small number of parts and which may be easily superposed by additional structure 50 or otherwise altered as desired.

55 Other and further objects of the invention may be more clearly understood from a consideration of the following specification which is taken in conjunction with the accompanying drawings, and in which

Fig. 1 is a perspective view of an assembled

structure showing a portion of one tier and one aisle, and embodying one form of the invention;

Fig. 2 is an enlarged vertical sectional view of the deck, being taken substantially on the line 2—2 of Figure 1;

Fig. 3 is a vertical sectional view, showing the connection between deck plates, being taken substantially on the line 3—3 of Figure 2;

Fig. 4 is an enlarged plan view of the star section supporting member or strut, showing the method of attaching vertically adjacent members together and of securing the deck plates to these members;

Fig. 5 is a plan view showing how adjacent deck plates are positioned with respect to each other and to the supporting members;

Fig. 6 is a plan view of one of the deck plates;

Fig. 7 is a sectional view taken substantially on the line 7—7 of Figure 6;

Fig. 8 is an enlarged sectional view taken substantially on the line 8—8 of Figure 6;

Fig. 9 represents the filler member or shim which is interposed between the ends of adjacent deck plates; and

Fig. 10 shows a rail attached to a deck plate.

Referring to the drawings and particularly to Figure 1, a supporting structure is shown consisting of a plurality of star-shaped structural elements or columns which will be generally indicated by the reference numeral 10, details of which will be more fully disclosed later in the specification.

The columns are preferably arranged in straight lines at points which define a plurality of equal rectangles. The lower columns are adapted to be secured to the main or ground floor by means of angle knees 11 which are suitably fastened at the floor of each column by bolts 12. Secured to the upper portion of each column by means of bolts 13 are rectangular deck plates 14. The ends of said deck plates terminate in downwardly projecting flanges 16 while the sides are terminated by downwardly projecting channel flanges 17. Parallel to and a short distance toward the center from the end flanges 16 are a pair of spaced bent up flanges or curbs 18 which may be formed integral with the deck plate 14. These flanges 18 are adapted to form parallel aisles 19 for each tier. Longitudinal openings 20 adjacent the flanges 18 serve as ventilators to conduct

fresh air or light from one tier to the next. The surface between curbs 18 may be covered with a composition sheet, block flooring, or any other suitable material 21. The end portions of the deck 14, commencing

adjacent the flange 16 and terminating at the opening 20, constitute the entire storage space of the structure. These portions serve to receive and support shelving or suitable book receiving units.

At convenient intervals and on both sides of the aisles are located cross-tie rods 22 which may be fastened from a point on the upper portion of one of the columns 10 to a point on the lower portion of the next adjacent column on the same side of the aisle. The extreme ends of the tie rods are provided with hooks 23 which are inserted in suitable openings conveniently located in the flanges of the column 10. Turnbuckles 24 or any other device for adjusting the length of the tie rods 22 are mounted thereon and serve as a means for tightening said rods to the desired tension.

It should be pointed out that between adjacent deck plates there is a narrow gap the width of which is dependent upon the thickness of the column flanges which support these plates. In order to bridge this gap and tie adjoining plates together to form a continuous deck, a shim 26 has been interposed between said plates which is secured to the adjacent vertical portions of the channel 17 in any suitable manner as by bolts 27. Shims 26 also lend additional resistance against bending to the I beam section formed by the two reversely disposed channels 17.

The deck plate 33, shown in Figure 10, is provided with curbs 34 which may be attached in sections or may be continuous throughout the length of the aisle. These curbs take the form of angle elements which are welded or bolted in place on the plates.

Suitable openings 28 (see Figures 8 and 9) through shims 26 and channel 17, receive and support conduits, water pipes, gas pipes and other conducting mediums 29. Since the interposed tiers as well as the adjacent deck plates are mounted on columns in exactly the same manner as the section shown in Figure 1, further description of the elements is believed to be unnecessary. Columns 10 may be continued upwardly by splicing additional columns of substantially identical cross section to the one beneath and may be accomplished in many different ways, one of which is clearly illustrated in Figure 1, 2, 3 and 4 of the drawings. Short sections of the angle plates 31 may be secured to the ends of abutting columns by means of bolts 32.

The columns 10, shown in the present structure are preferably formed from a pair of cold or hot rolled structural angles or bent up angles with the heels faced off at an angle to both flanges. The faces thus formed are brought together and welded or otherwise suitably joined. It should be noted in this structural section, the reversely disposed flanges lie substantially in the same plane and are particularly well adapted to be used in structures of the nature above described.

While applicant has shown and described but one modification of his invention, he does not intend to be limited thereto since it is obvious to those skilled in the art that other modifications

or adaptations may be made without departing from the spirit and scope of the invention as set forth in the hereunto annexed claims.

Having thus set forth my invention what I claim as new and for which I desire protection by Letters Patent is:

1. A deck plate for structural frames, channel flanges terminating the sides of said plate, integral curbs formed in said plate, said curbs serving to support flooring material and producing openings outside the flooring area which serve to conduct air and light above or below said plate.

2. In a deck for structural frames, a plate, upstanding means spaced inwardly from the ends of said plate, said means being alignable with the corresponding means of the next adjacent plate to provide substantially continuous curbs between which to locate and retain suitable flooring.

3. In a deck for structural frames, a plate, spaced upstanding means formed integral with the face portion of said plate, said means being spaced inwardly from the ends of said plate and alignable with the corresponding means of the next adjacent plate to provide substantially continuous curbs between which to locate and retain suitable flooring.

4. In a deck for structural frames, a plate, spaced flanges running transversely of the face portion of said plate, defining a flooring area, said flanges being removed from the ends of said plate, and walls defining ventilating openings in said portion outside of the flooring area.

5. In a deck for structural frames, a plate having a face portion, spaced vertical flanges formed from said portion, said flanges serving to locate and retain suitable flooring material, and walls defining openings in said portion outside of the flooring area.

6. In a library stack structure having a plurality of columns, a deck plate secured to each of said columns and serving to prevent lateral displacement thereof, spaced portions of said plate serving to receive and support shelving or book receiving units, and means interposed between said portions for locating and retaining suitable flooring material.

7. In a library stack structure having a plurality of columns, a deck plate secured to each of said columns and serving to prevent lateral displacement thereof, spaced portions of said plate serving to receive and support shelving or book receiving units, spaced flanges on said plate for locating and retaining suitable flooring material, and ventilating means between one of said portions and one of said flanges.

8. In a structural frame for library stacks having a plurality of uniformly spaced upstanding columns, a deck comprised of plates, each of said plates being directly joined to four adjacent columns, the end portions of said plates serving to receive and support shelving or book receiving units, curb means between said end portions for locating and retaining suitable flooring material, light and ventilating means between said curb means and one of said end portions.

ELMER W. COLEMAN.
